AIR REGISTER FOR BURNERS

Albert L. Baker, Summit, N. J., assignor to Gasoline Products Company, Inc., Jersey City, N. J., a corporation of Delaware

Application December 21, 1937, Serial No. 180,932

3 Claims. (Cl. 158—1.5)

This invention relates to air registers for fuel burners.

An air register constructed to embody my invention may be used with gas as well as oil firing. The air register is adapted to be attached to a furnace around an opening therein and is adapted to be held in fixed position around a burner or combination of burners. With a stationary air register embodying my invention and arranged around a furnace opening I am able to prevent short circuiting of the air around the air register so that all the air passing through the register is given a swirling motion and is directed toward the burner or burners for mixing with the fuel to be burned, whereby turbulence and intimate mixing of the air and fuel are obtained.

The air register constructed to embody my invention is provided with pivotally mounted vanes which open outwardly and which may be moved manually as a unit to desired positions to control the amount of air admitted to the burner or burners.

In the drawings:

Figure 1 represents a partial vertical longitudinal cross-section taken through an air register made according to my invention and in position around an opening in a furnace wall;

Figure 2 represents a partial transverse vertical cross-section taken substantially on line 2—2 of Figure 1;

Figure 3 represents a partial transverse vertical cross-section taken substantially on line 3—3 of Figure 1 with parts omitted to facilitate the disclosure; and

Figure 4 represents a vertical cross-section of a detail taken substantially on line 4—4 of Figure 1.

Referring now to the drawings, the reference character 10 designates a portion of a furnace wall having a burner opening 12. The refractory wall 14 around the burner opening is flared as at 16. A burner assembly 18 projects into the furnace and comprises a burner casing 20 which is mounted in a guide sleeve 22 held in fixed position in any suitable manner in an air register 24. The burner assembly is slidably mounted in the guide sleeve 22 as will be described in more detail hereinafter.

The air register generally designated 24 is rigidly secured to the furnace wall around the burner opening 12 for supplying air to the burner or burners of the burner assembly 18. Air vanes 26 are pivotally mounted on the air register and can be adjusted as a unit for controlling the

amount of air supplied to the furnace for the combustion of the fuel.

The air register 24 is preferably circular in shape and is open around its circumference so that air can be taken in through a large area. The air register 24 comprises a flanged member 28 having its flange 30 extending into the furnace opening 12. Member 28 is secured to the exterior wall of the furnace 10 in any suitable manner as by screws 32. A supporting plate member 34 having a central, inwardly-directed flange 36 for receiving and supporting guide sleeve 22 is spaced from member 28 by spacing members 38. Plate member 34 is secured to the plate 28 by elongated bolts or the like 40 which extend through 10 spacing members 38.

The vanes 26 are mounted to open outwardly between plate members 28 and 34 and are secured along one edge to shafts 42 mounted for oscillation so that when the shafts are moved the vanes 20 will be moved to open or closed position. The vanes 26 and shafts 42 extend at right angles to member 34. The mechanism for actuating the vanes will now be described. As shown in the drawing in Figure 3, the vanes are bent around the shafts 42 as at 44 and attached to the shafts in this way. Other means of securing the vanes to the shafts may be used. The shafts 42 are supported and mounted for oscillation in supporting plate member 34 and plate member 28 in 30 the following manner. Each shaft 42 extends through an opening 46 in the supporting member 34 and through an opening 48 in the flanged plate 28. The outer end of each shaft extends beyond plate member 34 as at 49. The support for the inner end of the shaft 42 in flanged member 28 may be omitted if desired. Each shaft may be provided with an abutment 50. The shafts 42 are preferably arranged in a circle and the vanes 26 are so arranged that their free edges 51 rest on the bent, pivoted edges 44 of the adjacent vanes in closed position as shown in Figure 3 so that the air openings in the air register are substantially completely closed and no air will pass through the register to the opening 12 in the furnace. When it is desired to move the vanes 26 to open position, an operating mechanism is employed which will be now described to move the free edges 51 of the vanes outwardly around shafts 42 as pivots as shown in dot and dash lines in Figure 3.

At its outer end or the end adjacent plate member 34, each shaft 42 is fixedly secured to one end of a link 52, the other end of the link being pivotally secured to one end of a connect- 55

ing rod 54. The other end of each connecting rod 54 is pivotally attached to a rigid projecting member 56 which forms part of a movable collar 58. The projecting members 56 extend from the periphery of the movable collar 58. The collar is supported on guide tube 22 for oscillation and by moving the collar, the associated parts and linkages 52, 54 and 56 will be moved to actuate each shaft 42 and this in turn causes movement 10 of each vane 26 as will be later described in more detail in the operation of the device.

The movable collar 58 has an operating member 60 extending therefrom which is provided with a handle 62 whereby it may be moved to any desired position to move the vanes 26 to any desired position between full open and closed positions. Operating member 60 is provided with a slot 64 to receive stationary, arcuate guiding member 63. Arcuate member 63 is secured to standards 20 68 by bolts 70, the standards 68 being rigidly secured in any suitable manner to cover member 72 which is secured to supporting plate member 34 by bolts 74 or in any other suitable manner. A wing nut 76 is threaded into operating member 25 60 and is adapted to be screwed against arcuate member 63 in order to hold the parts in any adjusted position.

The burner assembly is adapted to be moved longitudinally of the guide tube 22 so as to vary 30 the flame produced from the burner or burners. A gas burner 78 including burner casing 29 is slidably mounted in guide sleeve 22 and is secured to a vertical supporting member 33 in any suitable manner as by bolts 22, the lower end 35 of the supporting member 33 being provided with a slot 34 adapted to receive a horizontal supporting member 36 secured in any suitable manner to the exterior wall of cover member 72. (See Figs. 1 and 4.) A wing nut 38 adapted to engage 40 member 36 is provided for securing the gas burner in adjusted position. An oil burner 93 is supported by and extends through the gas burner 78 and is secured to a vertical supporting member 92 by bracket 94. The lower end of the 45 supporting member 92 is provided with a slot similar to slot 34 on the upright member 29 for the gas burner whereby the oil burner may be moved to the desired position. A wing nut 96 is provided for securing supporting member 92 and 50 oil burner 93 in adjusted position.

The gas burner 78 has a gas inlet 83 and a burner tip 100. The oil burner 93 has an oil inlet 102 and a burner tip 103. A deflecting member 106 may be used adjacent the gas burner tip 100. While I have shown an oil burner and a gas burner, it is to be understood that I may use only one burner; or both burners may be used.

The operation of my air register will now be described. When it is desired to begin operation of the burner, the wing nut 76 on the operating member 60 is loosened and the vanes 26 are moved to full open position by moving movable collar 58 to provide an excess of air for the burner or burners. The movable collar 58 is moved in a clockwise direction as viewed in Figure 3 in order to move the vanes 26 outwardly to full open position as shown in dot and dash lines in Figure 3. I prefer to have the vanes 26 open outwardly 70 because the area of opening or air admittance in full open position is greater than in a construction where the vanes open inwardly. By moving the collar 58 in a clockwise direction, arms 56 being connected thereto also move in a 75 clockwise direction. The connecting rods 54 be-

ing connected to arms 56 and to links 52 move the links in a counterclockwise direction. The links 52 are connected to shafts 42 which are secured to the vanes 26 so that movement of the links 52 causes counterclockwise movement of the shafts 42 and vanes 26 and the vanes move outwardly to open position as shown in Figure 3 in dot and dash lines. The shafts 42 are mounted for oscillation in supporting plates 28 and 34 as above described.

With the vanes 26 of the air register 24 in open position, the burner assembly 13 or each burner separately is moved to the left in Figure 1 after loosening wing nuts 88 and 96. Fuel is then admitted to the burner or burners and the fuel 15 streams are then ignited in the usual way. The vanes 26 are then moved in a closing direction to a position where proper mixing of fuel and air is obtained. The closing movement of vanes 20 26 is obtained by moving operating member 60 20 and movable collar 58 in a counterclockwise direction in Figure 3. My air register is adapted for use with oil firing as well as gas firing. Solid fuels may also be used.

By moving the burner or burners to the left 25 in Figure 1 from the position there shown, air admitted through the air register will be thoroughly mixed with the atomized oil or gas before the stream is discharged into the furnace. This will speed the ignition reaction of the gas 30 or oil in burning and the diameter of the flame will be reduced. If it is desired to increase the diameter of the flame, it is only necessary to push the oil or gas burner to the right in Figure 1. In this way the effect of air mixing with the 35 atomized oil or gas stream will be delayed and this will result in a greater flame diameter and a lower central velocity of the products of combustion.

The vanes 26 control the quantity of air admitted to the burner fuel outlet and direction of air flow. The vanes 26 give the admitted air a swirling or rotative motion. The air entering through the air duct or from the atmosphere is directed by the vanes 26 and vertically arranged 45 spaced members 28 and 34 toward the center of the burner immediately adjacent the burner fuel outlet with the desired velocity so that the air is mixed with the fuel and is not by-passed or short circuited around the burner assembly directly into the furnace. Due to the rotative velocity and swirling motion given to the air by the air register, a turbulent flow is obtained in the air-fuel mixture which produces intimate mixing and consequently better combustion. 50 Also the air passing into the air register has a relatively large velocity which carries the air toward the center of the air register, and due to the positioning and arranging of the vanes and the air register, the air is not short circuited into 55 the furnace but is directed toward the burner fuel outlet. From the description and drawings it will be seen that the air register 24 is positioned against the furnace wall and all air to the furnace must pass through the air register and be directed by the outwardly directed vanes toward the burner assembly and stratification of the fuel and air is prevented.

While I have shown and described one form of my invention, it is to be understood that this is 70 only for the purpose of an example and many modifications may be made within the scope of my invention.

I claim:

1. An apparatus of the character described in- 75

cluding an air register adapted to be positioned adjacent a furnace wall opening, a sleeve supported by said air register and adapted to receive a burner, a plurality of vanes mounted for pivotal movement on said air register and arranged near the periphery thereof for opening movement outwardly with respect to said air register, a horizontally arranged shaft rotatable on a horizontal axis for each vane, each vane being secured to its respective shaft whereby rotation of said shafts in one direction effects outward opening movement of said vanes, a link secured at one end to each shaft for moving said vanes, a collar mounted for oscillation on said sleeve, said collar having a plurality of spaced projecting members, and connecting rods between said links and said projecting members on said collar, each connecting rod having one end secured to the other end of its respective link and having its other end connected to a projecting member whereby the oscillatory movement of said collar effects movement of said shafts and vanes to control the amount of air passing through said air register.

2. An apparatus of the character described including an air register adapted to be positioned adjacent a furnace wall opening, a sleeve supported by said air register and adapted to receive a burner, a plurality of vanes mounted for pivotal movement on said air register and arranged near the periphery thereof for opening movement outwardly with respect to said air register, a rotatable horizontally arranged shaft for each of said vanes, each of said vanes having one edge portion secured to its respective shaft, links secured at one end thereof to said shafts for moving said vanes, a collar mounted for oscillation on said sleeve, connecting rods between the other ends of said links and said collar whereby movement of said collar effects movement of said shafts and vanes to control the amount of air passing through said air register, said collar having an operating member rigidly secured thereto and means for guiding the movement of said operating member and for holding said collar and vanes in adjusted position.

cured to its respective shaft whereby rotation of said shafts in one direction effects outward opening movement of said vanes, links secured at one end thereof to said shafts for moving said vanes, a collar mounted for oscillation on said sleeve, and connecting rods between the other ends of said links and said collar whereby the oscillatory movement of said collar effects movement of said shafts and vanes to control the amount of air passing through said air register.

3. An apparatus of the character described including an air register adapted to be positioned adjacent a furnace wall opening, a sleeve supported by said air register and adapted to receive a burner, a plurality of vanes mounted for pivotal movement on said air register and arranged near the periphery thereof for opening movement outwardly with respect to said air register, a rotatable horizontally arranged shaft for each of said vanes, each of said vanes having one edge portion secured to its respective shaft, links secured at one end thereof to said shafts for moving said vanes, a collar mounted for oscillation on said sleeve, connecting rods between the other ends of said links and said collar whereby movement of said collar effects movement of said shafts and vanes to control the amount of air passing through said air register, said collar having an operating member rigidly secured thereto and means for guiding the movement of said operating member and for holding said collar and vanes in adjusted position.

ALBERT L. BAKER.
